RADIANT ELEMENT FOR GAS HEATER

Roy A. Dudley, North Kenova, Ohio

Application September 21, 1955, Serial No. 38,017

Term of patent 7 years

(Cl. D81—10)

Fig. 1.

Fig. 2.

Fig. 3.

Figs. 1, 2 and 3 are front elevation, side elevation and top plan views, respectively, of a radiant element for gas heater embodying my design.

I claim:

The ornamental design for a radiant element for gas heater, as shown.
